ATTORNEY

UNITED STATES PATENT OFFICE.

GEORGE BRYAN, OF CHICAGO, ILLINOIS, ASSIGNOR OF ONE-HALF TO
ALPHONSO GOODRICH, OF SAME PLACE.

CAR-COUPLING.

SPECIFICATION forming part of Letters Patent No. 293,713, dated February 19, 1884.

Application filed June 11, 1883. (No model.)

To all whom it may concern:

Be it known that I, GEORGE BRYAN, a citizen of the United States, residing at the city of Chicago, in the State of Illinois, have invented a new and useful Improvement in Car-Couplings, of which the following is a specification.

The nature of this invention is to provide a self-adjusting link-supporter located within the draw-head, as will hereinafter be shown.

Figure 1 is a vertical sectional view. Fig. 2 is a front view of a draw-head, showing my improvement. Fig. 3 is a view of the self-adjusting link-supporter, and Fig. 4 is a view of one of the side pieces of the link-supporter.

Similar letters of reference refer to similar parts in the different drawings.

A is the draw-head of a car-coupling, having the pin B and link C. In the mouth of the draw-head is placed the self-adjusting link-supporter D, which is made in the form shown in Fig. 3. It is attached to the sides of the mouth of the draw-head by means of bolts passing through eyes or holes F at the upper

ends of the sides or arms E and into the sides 25 of the jaws. The link-supporter swings or plays freely upon these bolts, and is so suspended in the mouth of the draw-head that it hangs flush with the oval face of the head, as shown at Fig. 1. When the link C is inserted 30 in the draw-head, it rests upon this supporter. When two cars of equal height are coupled together, the link is in a horizontal position, as shown at a, Fig. 1; and when two cars of unequal height are coupled together, it is in 35 an oblique position, as shown at b and c, as the case may be. The widely-opened mouth of the draw-head freely allows this canting of the link, as required.

I claim—

40 In combination with a draw-head of a car-coupling, the self-adjusting link-supporter D, as and for the purpose shown.

GEORGE BRYAN.
